[57] **ABSTRACT**

A method is described for determining the downhole operating conditions of a hydraulic pumping system from measurements taken at the surface. Measurements of the surface flow rate and dynamic pressure of power oil used to drive a subsurface pump are made along with determinations of the friction factor of the conduit used to transport the power oil to the pump. This information is then combined to form a boundary valve problem based on the wave equation that describes the acoustic waves in the power oil. Solutions to the wave equation may then be used to determine the downhole conditions.

DIAGNOSTIC METHOD FOR SUBSURFACE HYDRAULIC PUMPING SYSTEMS

BACKGROUND OF THE INVENTION

This invention relates to a method for determining the performance characteristics of a pumping well. More particularly it is directed to a method of determining the downhole conditions of a hydraulic pumping system from surface measurements taken on the power oil used to drive the pumping system.

Subsurface hydraulic pumping systems provide one of the most effective means of lifting large volumes of oil from deep wells, and their use in modern production operations is rapidly increasing. Typically, a subsurface hydraulic pumping system consists of a reciprocating pump located at the production level of a well. Also located at that level is a downhole hydraulic engine for driving the pump. The downhole engine is driven by high-pressure power oil supplied by a prime mover and pump at the surface.

Although downhole hydraulic pumping systems have many advantages, they still lose efficiency over time and occasionally break down. Yet, when production from a well declines, it may be the result of many downhole conditions such as exhaustion of the oil reservoir or a loss in pumping efficiency. If the loss in production is due to the former, it may be advisable to shut down the well. But if the only problem is a bad pump, it may be replaced and profitable production resumed. Thus, it is of critical importance to know the condition of the downhole pumps. Yet it is very expensive and time consuming to haul them to the surface for visual inspection. A way of determining downhole pump conditions from surface measurements is critically needed.

With sucker rod-type pumping operations, downhole operating conditions can be determined by an analytical technique utilizing a polished-rod dynamometer. The dynamometer is an instrument that records the surface data necessary for use in the analytical technique as disclosed in U.S. Pat. No. 3,343,409, *Method of Determining Sucker Rod Pump Performance*, issued to S. G. Gibbs and copending U.S. Pat. application Ser. No. 658,407, filed Aug. 4, 1967, entitled *Method and Apparatus for Analyzing Sucker Rod Wave Motion* and having the same inventor, now U.S. Pat. No. 3,527,094.

However, these techniques are not applicable to subsurface hydraulic pumping systems since there are no sucker rods. Thus, it is a primary object of this invention to provide a method of determining downhole operating conditions for hydraulic pumps from surface measurements.

SUMMARY OF THE INVENTION

Broadly, the invention meets the objective of providing a method of determining downhole operating conditions in an hydraulically pumped well from data measured at the surface. This is achieved by first determining the friction factor of the conduit delivering the power oil to the downhole engine. Next the surface level prime mover and pump are actuated which causes the downhole pump to reciprocate. The dynamic pressure and flow of the power oil is then measured at the surface and recorded as a function of time. Finally, the flow and pressure data are combined with the friction factor determinations to establish the boundary value problem based on the wave equation that describes the movement of acoustic waves in the power oil as they travel from the downhole pump to the surface. With solutions to this equation in hand it is possible to accurately determine the dynamic pressure and the flow rate of the power oil at the downhole pump. This information is in turn used either to construct downhole dynagraph cards or to determine other downhole factors of interest such as pump intake pressure.

BRIEF DESCRIPTION OF THE DRAWINGS

FIG. 1 is a schematic diagram, partially in longitudinal section, showing the general arrangement of an hydraulic pumping system for an oil well;

FIG. 2 is a graphical illustration of the surface power oil velocity (flow rate) as a function of time;

FIG. 3 is a graphical illustration of the dynamic pressure of the power oil measured at the surface;

FIG. 4 is a circuit diagram of an electrical transmission line analogous to the power oil column; and

FIG. 5 is an analog computer utilizing the transmission line of FIG. 4 for quickly and accurately determining the downhole power oil pressure and flow rate.

DESCRIPTION OF THE PREFERRED EMBODIMENT

Referring now to FIG. 1 there is shown a well having a well casing 10 extending from the reservoir or fluid production interval 12 to the surface 14. Positioned within well casing 10 is a production tube 16 having an hydraulic engine 18 and a pump 20 located at the production interval 12. A power oil conduit 22 interconnects hydraulic engine 18 with a prime mover 24 on the surface which incorporates a pump (not shown). Prime mover and pump 24 supplies high-pressure power oil through conduit 22 to run hydraulic engine 18. Pump 20 is a conventional reciprocating pump typically used in downhole hydraulic pumping operations. Its function is to lift the oil, water, and/or gas production fluid of reservoir 12 along with the power oil to the surface through production tube 16 where it is exhausted through port 26 to storage. In the process, each time pump 20 makes a stroke, pressure and flow rate waves are transmitted to the surface through the power oil in conduit 22. In effect, the power oil acts as a transmission line.

The dynamic pressure of the power oil is measured at the surface by pressure transducer 28 and a signal representative thereof is transmitted via electrical lead 29 to recorder 30 where it is recorded on a separate track at some recording speed, V_1 . Likewise, the flow rate of power oil is measured by flow rate transducer 32 and a signal therefrom is transmitted via electrical lead 33 to recorder 30 where it is also recorded on a separate track. The pressure and flow rate are recorded as a function of time and would look like FIGS. 2 and 3 if drawn out on a strip chart.

The pressure and flow rate signals measured by transducers 28 and 30 respectively contain information about downhole equipment operation as well as information about the surface power oil pump 24. The method of this invention separates out the information relating to operating conditions at the downhole engine 18 and pump 20.

As is apparent from FIGS. 2 and 3, the pressure and flow rate signals are quite complex. In fact the complexity is such that visual interpretation thereof to infer downhole conditions is difficult, if not impossible. But if it were possible to measure the dynamic pressure and flow rate of the power oil as it entered the downhole engine, then downhole indicator cards, similar to dynagraph cards in rod-pumped wells, could be constructed. Such cards may be interpreted to determine not only the mechanical conditions and efficiency of the downhole equipment but also to determine the condition of the oil reservoir around the well bore.

Since measurement of the downhole pressure and flow rate is difficult, it is desirable to obtain such information from surface measurements. Thus, one aspect of this invention is the discovery, through extensive experimentation, that the power oil column acts as a good transmission line and is closely approximated by the following wave equation:

$$\frac{d^2h(x, t)}{dt^2} = a^2 \frac{d^2h(x, t)}{dx^2} - c \frac{dh(x, t)}{dt} \quad (1)$$

where:

- 70 a = velocity of pressure waves in the power oil in ft./sec.
 c = damping factor
 t = time in seconds
 x = distance along the power oil line from the surface in feet
 $h(x, t)$ = dynamic pressure head
75 g = acceleration of gravity in ft./sec.²

Consequently the desired information about dynamic pressure at the downhole equipment can be determined by solving equation 1 when x is equal to the depth of the downhole equipment.

The damping coefficient is defined by the following equation:

$$C=f(V/2D)$$

where:

V = average power oil velocity in ft./sec.

f = friction factor as determined from a Moody diagram

D = internal diameter of pipe in feet

To determine f , it is necessary to calculate the Reynolds number, the relative roughness of the pipe, and then read the friction factor from a Moody diagram which is known to those skilled in the art (i.e., at page 3-12 of Handbook of Fluid Mechanics, Streeter, Victor L., McGraw-Hill, 1961 Edition).

Reynolds number is given as

$$R=78.64(SG)(V)(D)/\mu$$

where:

SG = specific gravity of oil at mean well pressure and temperature

V = average power oil velocity in ft./sec.

D = internal diameter of pipe in feet

μ = viscosity of oil at mean well pressure and temperature (poise)

The relative roughness is given by:

$$r=(\epsilon/D)$$

where:

ϵ = pipe roughness (inches)

D = internal diameter of pipe (inches)

The velocity of the pressure wave in oil is determined by the following expression:

$$a=\frac{W}{g}\left(\frac{1}{K}+\frac{DC_1}{Ee}\right)^{-1/2}$$

where:

g = acceleration of gravity in ft./sec.²

D = internal diameter of pipe (inches)

e = thickness of pipe (inches)

E = Young's Modulus for steel = 4.32×10^9 (1b./ft.²)

K = volume modulus of fluid (lb./ft.²)

W = specific weight of fluid (1b./ft.³)

$C_1 = 0.95$

K is calculated from the compressibility of the fluids in the following manner:

$$K = \frac{144}{\text{Compressibility (volume/volume/p.s.i.)}}$$

Thus, the method requires that the above measurements be taken and combined to determine a and c .

In the solutions of equation 1 a set of boundary conditions is necessary. These conditions are supplied by the measurements of surface flow rate and dynamic pressure of the power oil. Preferably these measurements are in the form of curves of flow rate and dynamic pressure versus time as shown respectively in FIGS. 2 and 3. The boundary conditions are formulated analytically by approximating these curves with truncated Fourier series of the type:

$$h(o, t) = \frac{v_o}{2} + \sum_{n=1}^{\infty} v_n \cos n\omega t + \delta_n \sin n\omega t \quad (3)$$

and

$$V(o, t) = \frac{\sigma_o}{2} + \sum_{n=1}^{\infty} \sigma_n \cos n\omega t + \tau_n \sin n\omega t$$

where

$V(o, t)$ = power oil velocity at the surface $x=0$.

The Fourier coefficients σ , τ , δ , and v of equations 3 and 4 are evaluated from the measured data by conventional harmonic analysis.

Since the mechanics of the solution to equation 1 with boundary conditions is not part of this invention, they will not be included here. The solutions will merely be stated. However, a detailed solution to boundary condition problems of

this type is set forth in U.S. Pat. No. 3,343,409, *Method of Determining Sucker Rod Pump Performance* issued to Gibbs.

The equation for the dynamic pressure head in the power oil line at any depth x , and at any time t is given by:

$$H(x, t) = \frac{v_o}{2} + \sum_{n=1}^{\infty} P_n(x) \cos n\omega t + Q_n(x) \sin n\omega t \quad (5)$$

10 where

$$P(x) = [(K_n \cosh \beta_n x + \delta_n \sinh \beta_n x) \sin \alpha_n x + (\mu_n \sinh \beta_n x + v_n \cosh \beta_n x) \cos \alpha_n x] \quad (6)$$

and

$$15 Q(x) = [(-\mu \cosh \beta_n x - v_n \sinh \beta_n x) \sin \alpha_n x + (K_n \sinh \beta_n x + \delta_n \cosh \beta_n x) \cos \alpha_n x] \quad (7)$$

The formula for power oil velocity at depth x and time t is:

$$20 V(x, t) = \frac{\sigma_o}{2} + \sum_{n=1}^{\infty} R_n(x) \cos n\omega t + S_n(x) \sin n\omega t \quad (8)$$

where

$$25 R_n(x) = \frac{g\omega n}{a^2(\alpha_n^2 + \beta_n^2)} \{ [(-\alpha_n K - \beta_n \mu_n) \sinh \beta_n x - (\beta_n v_n + \alpha_n \delta_n) \cosh \beta_n x] \sin \alpha_n x \}$$

$$+ [(\beta_n K_n - \alpha_n \mu_n) \cosh \beta_n x + (-\alpha_n v_n + \beta_n \delta_n) \sinh \beta_n x] \cos \alpha_n x \}$$

and

$$30 S_n(x) = a^2(\alpha_n^2 + \beta_n^2) \{ [(-\beta_n K_n + \alpha_n \mu_n) \sinh \beta_n x + (d_n v_n - \beta_n \delta_n) \cosh \beta_n x] \sin \alpha_n x + [(-\alpha_n K_n - \beta_n \mu_n) \cosh \beta_n x + (-\beta_n v_n - \alpha_n \delta_n) \sinh \beta_n x] \cos \alpha_n x \}$$

In the foregoing equations

$$35 \omega = \frac{2\pi}{T}, \text{ where } T \text{ is the period}$$

$$40 v_n = \frac{\omega}{\pi} \int_0^T h(o, t) \cos n\omega t, n=0, 1, 2, \dots$$

$$\delta_n = \frac{\omega}{\pi} \int_0^T h(o, t) \sin n\omega t, n=1, 2, \dots$$

$$\sigma_n = \frac{\omega}{\pi} \int_0^T V(o, t) \cos n\omega t, n=0, 1, 2, \dots$$

$$\tau_n = \frac{\omega}{\pi} \int_0^T V(o, t) \sin n\omega t, n=1, 2, \dots$$

$$\alpha_n = \frac{n\omega}{a\sqrt{2}} \sqrt{1 + \sqrt{1 + \left(\frac{c}{n\omega}\right)^2}}$$

$$\beta_n = \frac{n\omega}{a\sqrt{2}} \sqrt{-1 + \sqrt{1 + \left(\frac{c}{n\omega}\right)^2}}$$

$$\mu_n = \frac{-a^2}{ng\omega} (\alpha_n \sigma_n + \beta_n \tau_n)$$

$$Kn = \frac{a^2}{ng\omega} (\beta_n \sigma_n - \alpha_n \tau_n)$$

60 The above equations 6 and 8 can be solved by programming a digital computer and supplying the test data in the proper form. The exact program of the computer can be developed by those skilled in the art, and the details thereof will vary from worker to worker. The computer output is a plurality of coordinate points that can be used to plot a downhole card.

65 The selected depth for which the equations are solved would be typically that of the downhole pump and engine; however, the equations are general and may be solved for any depth.

An analog computer can also be used to provide a solution to equations 6 and 8. An inspection of equation 1 shows that it has the same form as the equation of an electrical transmission line:

$$L \frac{d^2Q}{dt^2} + R \frac{dQ}{dt} - \frac{1}{c} \frac{d^2Q}{dx^2}$$

70 wherein L , R and c = inductance, resistance and capacitance

respectively, Q = charge in coulombs, x = distance in feet and t = time in seconds. This equation can be simulated by the circuit of FIG. 4 with magnitude of the capacitance, resistance and inductance being chosen to correspond to the features of the hydraulic system.

The equivalent circuit of FIG. 4 can be incorporated in a special analog computer or solved by a general purpose computer. A specialized computer is shown in block diagram form in FIG. 5. The computer of FIG. 5 can be connected directly to the transducers shown in FIG. 1. The computer will then supply a dynagraph card for any desired level in the system. The level of the dynagraph card can be selected by scaling the electrical elements of the equivalent transmission line shown in FIG. 4.

The circuit of FIG. 5 uses a recorder 30 to record the pressure and flow rate signals generated by the transducers of FIG. 1. The recorder can be a magnetic tape recorder with provisions for playing back the recorded signals at approximately 100 times the recording speed. It is preferred that the playback speed be greater to reduce the size of the elements in the equivalent transmission line of FIG. 4 and improve the performance of the system. The recorder supplies the two signals to a signal generator 32 that drives the analog computer to produce a dynagraph for the desired level.

The transmission line 34 is shown in detail in FIG. 4 and consists of resistance, inductance and capacitance. The exact size of the elements will depend upon the physical characteristics of the power oil conduit and its length and the characteristics of the power oil.

The transmission line 34 is connected to the recorder 36 that includes an oscilloscope for displaying the developed signal. Of course, the recorder 36 also includes circuits for adjusting the signals and adding fixed constants such as hydrostatic pressure. The signal displayed on the oscilloscope will be in the form of a dynagraph card for the selected depth. The signal on the oscilloscope can be photographed to obtain a permanent record of the dynagraph card.

I claim as my invention:

1. A method of determining downhole operating conditions of a hydraulically driven pumping well wherein a reciprocating pump is located below the fluid level of the well and is driven by a downhole hydraulic engine which in turn is driven by high-pressure power oil supplied through a conduit by a prime mover and pump at the top of the well, said method comprising:

1. determining the damping coefficient of said power oil conduit by measuring the average power oil velocity and physical characteristics of said power oil conduit;
2. determining the pressure wave velocity in the power oil by measuring the compressibility and specific weight of said power oil and thickness of said power oil conduit;
3. actuating said prime mover to reciprocate said downhole pump whereby said downhole pump generates acoustic

waves in said power oil that move from said downhole pump to the top of said well;

4. measuring and recording the dynamic pressure and flow of said power oil as a function of time;
5. selecting a depth within the well to be investigated and combining the damping coefficient determined in step (1) and the pressure wave velocity determined in step (2) with said dynamic pressure and flow data measured in step (4) to establish the boundary conditions to the wave equation that describes the movement of acoustic waves in a long column of high-pressure power oil whereby the dynamic pressure and flow rate of the power oil may be determined at said depth; and
- 15 plotting a curve of dynamic pressure versus flow rate at said selected depth.

2. The method of claim 1 wherein measuring said damping coefficient comprises:

- measuring the average power oil velocity;
measuring the internal diameter of said power oil conduit;
measuring the roughness of said power oil conduit;
determining the friction factor from a Moody diagram; and
combining the above measurements according to the following expression:

$$C=f(V/2D)$$

3. The method of claim 2 wherein determining said pressure wave velocity comprises:

- measuring the compressibility of said power oil;
measuring the specific weight of said power oil;
measuring the thickness of said power oil conduit; and
combining the above measurements with the internal diameter of said power oil conduit measured in claim 3 according to the following equation:

$$a = \frac{W}{g} \left(\frac{1}{K} + \frac{DC}{Ee} \right)^{-1/2}$$

4. A method of determining the downhole operating conditions of a hydraulically driven pumping well as set forth in claim 1 wherein said curve is plotted for any desired depth level in the well by utilizing the relationships of dynamic pressure versus time and flow versus time as expressed respectively by the following equations:

$$H(x,t) = \frac{v_o}{2} + \sum_{n=1}^{\infty} P_n(x) \cos n\omega t + Q_n(x) \sin n\omega t$$

and

$$V(x,t) = \frac{\sigma_o}{2} + \sum_{n=1}^{\infty} R_n(x) \cos n\omega t + S_n(x) \sin n\omega t$$

* * * * *
